CLAIM

The ornamental design for a hand actuated vehicle radiator cap remover, as shown.

DESCRIPTION

FIG. 1 is a perspective view of a hand actuated vehicle radiator cap remover, showing our new design;

FIG. 2 is an elevational view of one side, the opposite side being a mirror image thereof;

FIG. 3 is a top plan view thereof;

FIG. 4 is a bottom plan view thereof; and,

FIG. 5 is a sectional view thereof, the plane of the section being indicated by the diametral line 5—5 in FIG. 3.

FIG. 1.

FIG. 2.

FIG. 5.

FIG. 3.

FIG. 4.
